SURGICAL INSTRUMENT

Edgar F. Pixler, Leadville, Colo.

Application January 5, 1940, Serial No. 312,593

7 Claims. (Cl. 27—24)

This invention relates to surgical instruments, and more particularly to an instrument designed for removing liquids from the cavities of autopsied bodies.

5 An important object of the invention is to provide an instrument of this character which will accomplish its purpose readily and easily, and one which will prevent the hose or tube connected with the device from clogging, to impair the efficiency of the instrument, by preventing pieces of tissue or semi-solids from entering the tube.

10 Another object of the invention is to provide a surgical instrument for removing liquids from cavities of autopsied bodies, which may be positioned without regards to skill and accuracy, the construction of the device insuring the true operation of the instrument whether the instrument is submerged into all types of viscera or inserted under the viscera.

15 Still another object of the invention is to provide an instrument of the suction tube character wherein the shape of the shield or guard will insure the maximum efficiency by permitting the suction tube to remain submerged when held in a comfortable position for the operator.

20 A further object of the invention is to provide an adjustable tube which may be adjusted with respect to the guard or shield forming a part of the instrument, thereby permitting the very close removal of any liquids from pockets, hollows or

25 the bottoms of cavities. With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

30 Referring to the drawing:

Figure 1 is an elevational view of a surgical instrument constructed in accordance with the invention.

35 Figure 2 is an enlarged sectional view through the instrument, illustrating the guard.

40 Figure 3 is a similar longitudinal sectional view illustrating the adjustable tube as positioned for very close removal of liquids from pockets or cavities, in which the instrument is positioned.

45 Figure 4 is a sectional view taken on line 4—4 of Figure 3.

50 Referring to the drawing in detail, the body portion of the device is in the form of a tube in-

dicated by the reference character 5, the tube being provided with a disk-like enlargement 6 disposed in spaced relation with one end of the tube. A threaded flange indicated at 7 is formed on the disk-like enlargement 6 and is 5 adapted to receive the internal threads formed at the enlarged end of the guard 8, whereby the guard may be readily and easily removed or replaced.

The guard is substantially inverted cone-shape, 10 the free end of the guard being flat as at 9, and provided with openings 10.

15 Openings 11 are formed in the guard and are arranged so that liquid may enter the guard at points throughout the length thereof, or at points 15 wherever the guard may lie directly over the liquid to be removed.

An enlargement indicated at 12 is formed on the body portion 5, at a point in spaced relation with the free end of the body portion, the enlargement providing a stop against which one end of the adjustable tubular section 13 engages to restrict inward movement of the adjustable tubular section 13. An arm indicated at 14 extends from the inner end of the adjustable tubular 25 section 13, and passes through an opening in the disk-like enlargement 6, where it is provided with a finger piece 15 whereby the arm and adjustable tubular section may be moved longitudinally of the body portion 5, to adjust the section 13. 30

When a close removal of liquids from pockets or cavities is desired, the tube 13 is moved to the position as shown by Figure 3 of the drawing. In this position, entrance of material through the openings 11 of the guard is prevented, with the exception of the openings 10, which establish communication with the body portion and confine the suction through the body portion and guard, to a small area, to accomplish the purpose. 40

In the use of the device, the suction tube or hose from a vacuum bottle or tank, hydro-aspirator suction pump or other device commonly used in connection with tubes of this character, and the end of the body portion carrying the 45 guard or shield, is inserted into the viscera or positioned directly thereunder. The action of the suction device will now draw the liquids and semi-liquid material through the openings of the guard, and through the body portion and tube connected therewith.

From the foregoing it will be seen that due to the construction of the shield or guard, it is unnecessary to accurately position the device to accomplish its purpose, and that by adjusting 55

the tube 13 of the device, a very close removal of any liquids will be assured.

What is claimed is:

- 5 1. A surgical instrument for removing liquids and semi-liquids from autopsied bodies, comprising a tubular body portion to which a suction tube is connected, and a guard housing on one end of the body portion and having openings formed therein permitting material to pass into the guard and the end of said body portion extending into the guard being open, whereby material entering the guard is drawn into the body portion when suction is created through the body portion.
- 10 15 2. A surgical instrument for removing liquids and semi-liquids from autopsied bodies, comprising a tubular body portion to which a suction tube is connected, a guard housing on one end of the body portion, the guard being spaced from the body portion providing a passageway between the body portion and guard, said body portion having an open end, said guard having openings through which material may pass to the space between the guard and body portion and into the body portion through the open end thereof, when suction is created through the body portion.
- 20 25 30 35 40 3. A surgical instrument for removing liquids and semi-liquids from autopsied bodies, comprising a tubular body portion to which a suction tube is secured, an inverted frusto-conical guard housing one end of the body portion, said guard having openings in the wall thereof through which material passes to the body portion, and said guard being spaced from the body portion providing a passageway between the body portion and guard, and the end of the body portion housed by said guard being open, whereby material entering the passageway may enter the body portion.
- 45 4. A surgical instrument for removing liquids and semi-liquids from autopsied bodies, comprising a tubular body portion to which a suction tube is secured, an inverted frusto-conical guard having openings in the wall thereof, positioned on one end of the body portion, an adjustable tubular section mounted on the free end of the body portion and adapted to move into engage-
ment with the free end of the guard, cutting off certain openings of the guard and establishing communication with the body portion, through openings in one end of the guard, whereby material is drawn through the body portion when suction is created through the body portion.
- 5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640

5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640

6. A surgical instrument for removing liquids from autopsied bodies, comprising a tubular body portion to which a suction tube is connected, a frusto-conical guard positioned on one end of the body portion and spaced therefrom, providing a passageway between the body portion and guard, the end of the body portion being spaced from the end of the guard, and means for cutting off certain of the openings of the guard restricting the suction created through the body portion to the openings in the free end of the guard.

7. A surgical instrument for removing liquids from autopsied bodies, comprising a tubular body portion to which a suction tube is secured, an inverted frusto-conical guard positioned on one end of the body portion and having openings, said guard being supported in spaced relation with the body portion providing a passageway around the end of the body portion closed by said guard, and an adjustable member on the body portion and operating within the guard for cutting off certain of the openings of the guard and restricting the suction through the body portion to predetermined openings of the guard.
